UNITED STATES PATENT OFFICE.

EARL A. THISSELL AND WILLIAM H. WILDER, OF FLORENCE,
MASSACHUSETTS.

DESIGN FOR A STOVE.

SPECIFICATION forming part of Design No. 21,896, dated October 11, 1892.

Application filed August 12, 1892. Serial No. 442,911. Term of patent 14 years.

To all whom it may concern:

Be it known that we, EARL A. THISSELL and WILLIAM H. WILDER, of Florence, in the county of Hampshire, State of Massachusetts, 5 have invented and produced a new and original Design for Oil and Gas Stoves, of which the following is a full, clear, and exact specification.

In the accompanying drawing we have represented the design in front elevation.

The leading feature of the design consists in the peculiar configuration of the combustion-chamber. In the drawing this chamber is indicated at A. Its general shape is rectangular, 15 while its sides and front and back, instead of being perpendicular, are curved, slightly bulging from the top to the bottom of the chamber,

giving a distinctive appearance to the stove. This chamber is surrounded by a cylinder and an ornamental cap-plate of ordinary shape 20 and appearance, and below the fire-chamber is an ornamental base of substantially-ordinary appearance.

We claim—

The design for oil and gas stoves, as herein 25 shown and described.

In testimony whereof we affix our signatures in presence of two witnesses.

EARL A. THISSELL.
WILLIAM H. WILDER.

Witnesses:

HATTIE M. GATES,
LOUIS H. WARNER.
